CLAIM

The ornamental design for a modular support panel as shown and described herein.

DESCRIPTION

FIG. 1 is a top perspective view of a modular support panel, showing a first embodiment of our new design:

FIG. 2 is a top view thereof according to FIG. 1;

FIG. 3 is a bottom view thereof according to FIG. 1;

FIG. 4 is a side view thereof according to FIG. 1;

FIG. 5 is an end view thereof according to FIG. 1;

FIG. 6 is a top perspective view of a modular support panel showing a second embodiment of our new design within a first environment of use; and,

FIG. 7 is a top perspective view thereof, shown within a second environment of use.

The modular support panel is shown with broken lines. In FIGS. 1-5, the broken lines depict portions of the article that form no part of the claimed design. In FIGS. 6 and 7, the broken lines depict environmental subject matter that forms no part of the claimed design.

In FIGS. 1-4, the modular support panel is shown with symbolic breaks in its length. The appearance of any portion of the article between the break lines forms no part of the claimed design.
